DOUBLE SECURITY COIN COLLECTING SYSTEM
Louis L. Epstein, 25 Van Velsor Place, Newark, N.J., and
Julius Epstein, 70 S. Main Ave., East Orange, N.J.
Filed Sept. 19, 1962, Ser. No. 224,783
1 Claim. (Cl. 194—1)

This invention relates to a coin collecting system to be used by various kinds of coin-operated vending machines, as cigarette and music machines, for example.

The system herein disclosed affords double security, and comprises, in combination, an electrically operated counter, adapted to separately register, or count and record coins of different denominations, a coin selector-rejector adapted to reject spurious or counterfeit coins and to pass valid ones, electrical means adapted to actuate said counter when a valid coin passes through said selector-rejector, and a coin vault adapted to receive coins from the selector. The coin vault is preferably of the pilfer-proof type, as illustrated in the present drawings, is releasably locked to the selector-rejector, and is placed within the casing of the machine, as is the rejector, and also, if desired, said coin register.

In the drawings:

FIGURE 1 is an elevational view of the combination of a coin counter, a selector-rejector, and a coin receptacle, with a general diagram of an electrical circuit within the selector-rejector; and

FIGURE 2 is a broken-away elevational view of the coin receptacle.

Referring to the drawings for a detailed description, the numerals 5, 6 and 7 indicate respectively an electrical counter, a coin selector-rejector, and a coin vault. The counter has four registers, one for each coin denomination from 5 to 50 cents. The coin selector-rejector, herein after in the specification termed the S-R, has slots 9, 10, 11 and 12, one for each of the indicated coin denominations. As the construction of an S-R is known, it need only be recalled that there is a chute 50 or tube connected to each coin slot, and that there is an electric switch in each chute which is closed by a coin as it passes therethrough, the switches being numbered 15, 16, 17 and 18, corresponding to the slots 9-12 respectively. The internal structure of the counter 5 is also known. The closing of any switch actuates the corresponding individual counter, the S-R being electrically connected, as known, to the counter 5, by a cable 3, and the counter 5 provided with power through a cable 4. The number of coins of each denomination deposited is thereby recorded. Although known, it may be added that spurious coins are not counted, being ejected through the tube 20 which extends to the exterior of the machine.

The coins passing through the body of the S-R fall through a short chute 21 at the bottom of the same and into a coin vault 7. The coin vault is releasably locked to chute 21 by a lock 23 for removal by a collector, who then locks in an empty vault. The coin vault comprises a flanged top 22 at the upper end, from which depends a receptacle 24, which is shown as a bag, but is not limited to such. The bag may be releasably locked to the top as shown in Patent 2,973,138, issued to Louis L. Epstein.

FIGURE 2 shows the coin vault 7 as comprising a hopper 27 formed in the top 22 of the vault and extending somewhat therbelow, through which coins pass from chute 21 of the S-R. The coins from the hopper fall

2

through a coin retainer 30 which is open at its upper and lower ends and is secured to, and depends from, the hopper, and then into the bag 24 through the bottom opening of the retainer. This retainer contains a number of plates suspended from pivotally mounted rods, which plates are so arranged, and of such size, that, if the coin vault, after detachment from chute 21, is inverted in an attempt to shake coins out of it, the plates, all falling to one side or the other, are long enough to contact each other and form a barrier which retains the coins. More specifically, the uppermost plate 33 is angular, in the form of an inverted V, and extends substantially from the front to the back wall, and is secured at its apex to a light rod 34 which is rotatably held in opposite sides 5 of the retainer. Under plate 33, there is a pair of spaced straight plates 37 and 38 which respectively depend from rods 39 and 40; these rods are at the same level and are rotatably held in opposite sides of the retainer. Below and between plates 37 and 38, there is a plate 42 suspended from a rod 43 which is likewise rotatably journaled to the retainer. Additionally, there are two angular end plates 45 and 46 depending respectively from rotatable rods 47 and 48. All the plates extend substantially across the inside of the retainer.

It will be seen from the foregoing description of one embodiment of the invention that the combination of components affords double the security of the usual coin collecting system. Changes within the ordinary skill of the art may be made without departing from the inventive concept.

What is claimed is:

A double security coin collecting system comprising an electrically operated register adapted to separately count and record coins of different denominations, a coin selector-rejector having slots to receive respectively coins of different denominations and comprising coin chutes adapted to receive coins from their respective coin slots, electrical means associated with said slots and adapted to effect the actuation of said register when a coin passes 35 through one of said slots, a pilfer-proof vault adapted to receive coins, means detachably locking said vault to the selector-rejector, said coin vault having an open top to receive coins, a coin retainer within said coin vault, a plurality of depending, pivotally mounted plates in said 40 retainer positioned to allow coins to flow therebetween, said pivotally mounted plates being further adapted to move, when said vault is inverted, to pivot and close openings through which said coins would otherwise pass, said retainer having a coin slot at its lower end below said 45 plates, and a flexible coin receptacle enclosing said retainer.
